GUN-MOUNT

Application filed March 15, 1930. Serial No. 436,091.

This invention relates to a gun-mount and is particularly useful for mounting a gun in connection with aeroplanes and elsewhere in which the conditions for mounting and handling the gun are similar thereto or analogous in whole or in part. In this connection the gun to be mounted will ordinarily be of the machine gun type but the invention is not limited to the mounting of any particular type of gun nor to any particular use such as for aeroplanes except as specifically required by the claims.

An object of the invention is to provide a gun-mount whereby the gun can be readily trained and elevated and wherein the act of training the gun does not interfere with or disturb the degree of elevation at which the gun may have been set and vice versa.

Another object is to provide a gun-mount wherein the adaptations are such that the gunner, in the aeroplane for instance, is not exposed to the wind pressure in order to operate the gun, but on the contrary can do so perfectly from a protected position in the plane.

Another object is to provide a gun-mount wherein the means for training the gun and for elevating it are non-interferingly independent of each other and wherein the hand-controls for said means are conveniently mounted in two adjacent concentrically mounted hand-wheels adapted to be located for operation by the gunner from a protected position in the plane.

Another object is to provide a gun-mount and operating mechanism therefor whose construction enables the gun to be operated from an upright position relatively to the fuselage of the plane or from an inclined position over either side of the fuselage, and to enable these changes to be made quickly and at will, thereby greatly increasing the field of action and range of usefulness of the gun.

Another object is to provide a gun-mount having some or all of the foregoing characteristics and which will accomplish these by a simple, easily operated and dependable mechanism, and wherein the total weight is adapted to be kept down to a minimum.

Other objects will be in part apparent to those skilled in the art or in part pointed out hereinafter.

The invention accordingly consists in the features of construction, combinations of elements and arrangements of parts as will be exemplified in the structure to be herein-after described, and the scope of the application of which will be indicated in the following claims.

In order that the invention may be readily understood and its advantages from a practical standpoint fully appreciated, reference may be had to the accompanying drawings showing one of the preferred forms of embodiment which the gun-mount of the present invention is adapted to take. The preferred illustrative embodiment which I have chosen for this purpose is one which is especially adapted for use in connection with aircraft such as aeroplanes, and on this account the drawings show an aeroplane in connection therewith.

In the drawings, Fig. 1 is a vertical mid-section partly in elevation of said gun-mount within my invention;

Fig. 2 is the same except that the section is taken at right angles to that in Fig. 1, in other words, making comparison with Fig. 1, the section in Fig. 2 is taken in a direction which is transversely across the fuselage of the plane;

Fig. 3 is a horizontal section partly in plan on the line 3—3 of Fig. 1;

Fig. 4 is a side elevation of an aeroplane equipped with the gun-mount, the side of the fuselage being broken away to reveal the otherwise hidden portion of the gun-mount; and

Fig. 5 is a transverse section taken through the fuselage in front of the gun-mount looking rearwardly and showing the gun-mount in elevation.

Similar reference characters refer to similar parts throughout the several views.

Referring to the drawings, the machine gun 1 (Fig. 4) is mounted and rigidly secured in a gun carrier 2 which in turn is supported on a hollow head generally designated 3 which in turn is supported on a hollow body portion

generally designated 4 provided with means for rotatably supporting the hollow head 3 on said body portion so as to be rotatable about the axis indicated by the dotted line 5 in Fig. 1. The hollow body portion 4 is in turn supported on a stem 6 whose lower end is pivoted by pivotal connection 7 to a foot 8 which is secured to the floor construction 9 (Fig. 4) of the fuselage, said pivot being ar-

10 ranged to permit the gun-mount to be swung in a plane transverse to the fuselage from the upright position shown in the drawings to a position at either side of the fuselage.

The gun carrier 2 consists of an open-ended metal trough of U-shaped cross-section within which the gun is adapted to be received and secured therein by means of clamps or bolts not shown. The bottom of the carrier is provided with a lug 10 having trunnions 11 journaled in bearings in the upper ends of the parts 12, the latter being secured by their foot portions to the top 13 of the head 3. The aforesaid side bearing parts 12 are shown in vertical cross-section in Fig. 2 and in elevation in Figs. 1 and 4, in Fig. 1 the part being merely indicated by the dotted line 12. In Fig. 2, 12a is a vertical rib for stiffening and strengthening the bearing parts 12.

The rotatable head generally designated 3 consists of a metal cylinder 14 to which the top 13 is secured by the angle irons 15. The lower end of this cylinder is received down through a stationary sleeve 16 secured by its flanged foot portion to the top of the aforesaid body portion, generally designated 4, of the gun-mount. It will be understood that the cylindrical head 3 is supported by the body portion 4 and that the cylinder 14 of the former is rotatable within the sleeve 16 of the latter.

the latter. A worm wheel generally designated 17 is secured to the lower end of the cylinder 14 of the head 3. This consists of a flat ring 18 having at its inner periphery two oppositely directed flanges 19 and 20. The flange 19 fits within the lower end of the cylinder 14 and is rigidly screwed, bolted or riveted thereto. The outer periphery of the ring 18 projects radially beyond the wall of the cylinder 14 and is provided with the gear teeth which makes of the member a worm wheel 17. The lower flange 20 is received with bearing fit into a cylindrical walled recess in a horizontal plate 21 supported between the walls of the body portion 4, and the edge of said flange rests upon a shoulder 21a of said plate, forming the bottom of said recess. To hold the cylinder 14 of the head down in its described proper position relative to the body portion 4, I provide the member 46 secured to the plate 21 adjacent the worm wheel 17, said part 46 having an inwardly directed flange 46a which overlies the top of the worm wheel and has sufficient annular length to prevent said wheel and the attached cylinder 14 of the

head 3 from becoming displaced vertically relatively to the body portion 4, but does not interfere with the free rotation of the cylinder and the worm wheel relatively to the body portion 4. In mesh with the worm wheel 17 is a worm 22 on a shaft 23 whose ends are journalled in suitable bearings provided therefor in the side walls of the body portion 4.

The means for operating the worm shaft 75
23 and worm 22 to rotate the worm wheel 17
and attached head 3 comprises the follow-
ing. 52 is a hand wheel whose hub is secured
to a shaft 22a turning in a sleeve 24 mounted
to turn in a cylindrical boss 25 on the wall of 80
the body portion 4, the inner end of said shaft
22a being journaled in a bearing supported
by the opposite wall 26 of the body portion
4. The gear 27 on this shaft is in mesh with
the gear 28 on a stud 29 supported by the 85
wall 26, and the gear 28 is in turn in mesh
with a pinion 30 on the before mentioned
shaft 23. Thus by turning the hand wheel
52, the gunner through the described gearing
can rotate the head 3 about its axis 5 and 90
thereby train the gun carried by said head
through any angle in either direction.

The means for elevating the gun comprises the following. 31 is a hand wheel whose hub 31a is secured to the sleeve 24 between the other hand wheel 52 and the outside of the body portion 4. (32 is a washer surrounding the shaft 23 and located between the hub of the wheel 22 and the outer end of the sleeve 24 to serve as a spacing washer between the hubs of the two wheels 52 and 31.) This sleeve 24 projects through and turns in the stationary cylindrical boss 25. The free end of this sleeve 24 within the body portion 4, carries a bevel gear 33 secured thereto by 105

carries a bevel gear 33 secured thereto by the hub 33a of said gear. 34 is a bevel gear pinion in mesh with 33, said pinion being mounted on the lower end of the flexible shaft generally designated 35. This flexible shaft consists of a middle and two end portions joined by universal joints 35a. The lower end portion of the flexible shaft is journaled in a bearing provided for it in the heretofore described horizontal plate 21 across the interior of the body portion 4. The upper end of the flexible shaft is journaled in a bearing provided for it in the top 13 of the rotary head 3. 36 is a bevel gear disposed flatwise relatively to the top 13 of the head 3 secured by its hub 36a to the free upper end of the flexible shaft. It will be noted that the rotary axis of said gear 36 is eccentric relative to the axis 5 about which the head 3 rotates. 37 is a bevel gear pinion in mesh with the aforesaid gear 36 so that said pinion 37 and the bite between the pinion and said gear are preferably, substantially or approximately in the rotary axis 5 of the head 3. For support this pinion 37 is secured to a shaft 38 paralleling the top portion 13 of 130

the head 3 and having its ends journalled in bearings supported by upstanding lugs 39 from said top portion 13. 40 is a worm carried by the shaft 38, said worm being in mesh 5 with the worm wheel 41, the latter being an 180° segment of a worm wheel rigidly secured to the heretofore described lug 10 of the gun carrier 2.

Thus by operating the hand wheel 31, the 10 gunner can give any desired degree of elevation to the gun by means of the just described mechanism, comprising briefly the aforesaid bevel gears 33 and 34, the flexible shaft 35, the bevel gears 36 and 37 on top of the rotary 15 head 3 and finally the worm 40 and worm wheel 41, the latter tilting the gun carrier 2 on its trunnions 11 to point the gun with the desired angle of elevation.

It will be especially noted that the 20 respective mechanisms with their hand controls 31 and 52 for respectively elevating and training the gun, do not interfere with each other. Thus if the gunner has operated the hand wheel 31 to give the gun a desired elevation, the subsequent operation of the training hand wheel 52 will not affect said elevational adjustment. I have devised my present invention to secure this non-interference between the respective controls and for this 25 purpose in the illustrative embodiment I have located the axis of rotation of the gear 36 supported by the top of the head 3 so as to be eccentric relative to said rotary axis of the head. The result is that rotating the head 3 in order to train the gun does not cause the bevel gears 37 and 36 to turn relatively to each other. On the contrary, they are merely carried around along with the head 3, the gear 36 being carried in a circular orbit about 35 the rotary axis 5 and about the gear 37 which preferably is substantially coincident with said axis. The result is that no matter to what extent or in which direction the head 3 is rotated, it produces no relative turning 40 movement between the bevel gears 36 and 37, and therefore the worm 40 and worm wheel 41 remain stationary and hold the gun fixed in whatever elevational adjustment it may have.

50 The foregoing is a very different condition from that which would exist if the axis of rotation of the gear 36 instead of being eccentric were to be placed substantially or approximately concentric with the rotary axis 5 of the head 3. The result would be that whenever the head 3 was rotated, the pinion 37 would be carried by the head in a circular orbit about the rotary axis 5. On the other hand, the gear 36 would remain stationary 55 in spite of the rotation of the head because in accordance with the assumption it is at the center of motion or in the rotary axis 5 of the head. In short, the rotation of the head would carry the pinion 37 about the axis of 60 the stationary gear 36, which latter would

act like a stationary rack and would necessarily cause the pinion 37 to rotate and thereby operate the worm 40 and worm wheel 41 to change the elevation of the gun and throw it out of any elevational adjustment which 70 may have been previously given to it.

Further it will be noted that the invention provides not only for the hand controls 52 and 31 to be conveniently close together for operation by the gunner, but also provides 75 for a location for said controls well down on the gun-mount where the gunner will be protected within the fuselage of the aeroplane or by a special shield or equivalently operating protecting part in case the gun is used in 80 some other location than on the fuselage of an aeroplane. Thus in the illustrated embodiment, it will be seen that the hand wheels 52 and 31 mounted on the body portion 4 of the gun-mount are located below the sides of 85 the fuselage and this is accomplished by keeping the body portion 4 of the gun-mount low relatively to the bottom of the fuselage and by making the rotary head portion 3 of the gun-mount relatively high so as to support the gun sufficiently above the fuselage for effective operation. With the protected location of the hand controls provided by my invention, the gunner is not exposed to 90 any wind pressure much less to the terrific 95 wind pressure created by an aeroplane in flight, which often becomes so great that a gunner in an exposed position attempting to operate exposed controls is seriously handicapped in operating them accurately and indeed is often prevented from operating them at all, by being glued by the pressure, body 100 and arms, against the gun.

Finally, the preferred embodiment of the 105 invention provides for swinging the gun-mount from the upright position shown in the drawings, such as Fig. 4, into inclined positions at either side of the fuselage so that the gun overhangs the side of the fuselage and can be fired up and down and in other 110 directions from that position. This swinging of the gun-mount in a plane transverse to the fuselage is permitted as heretofore described by the pivotal connection 7 between the stem 6 of the gun-mount and the foot 8 115 secured to the floor construction 9 of the aeroplane at the bottom of the fuselage. To support and transversely guide the gun-mount, I provide two arcuate members supported transversely relatively to the fuselage 120 with the body portion 4 of the gun-mount between them. These arcuate members 42 are in turn supported from the floor construction of the aeroplane by legs 43 which are inclined as shown in Fig. 4, to act as braces for giving 125 increased rigid support to the guides 42. The body portion 4 of the gun-mount has a pin 44 (Fig. 5) projecting from its front wall and preferably a similar pin, not shown, projecting from its rear wall, adapted to ride along 130

the arcuate upper edge of the members 42 and to be received into engagement with the spring clips 45 carried by the members 42. Fig. 5 shows three of these spring clips positioned respectively at the middle portion of the arcuate member 42 and at the two end portions thereof. Each spring clip is adapted to releasably engage the pin 44 of the gun-mount and to hold the gun-mount in that position until the gunner desires to shift the mount into another firing position by swinging it as aforesaid in a plane transverse to the fuselage.

It will thus be seen that the foregoing gun-mount has a relatively simple construction and embodies easily operated and dependable mechanism and that the total weight thereof is adapted to be kept down to a minimum, which is especially necessary in a gun-mount for use in connection with aeroplanes.

As a number of possible embodiments may be made of the above invention, and as numerous changes might be made in the embodiment above set forth without departing from the spirit and scope of the invention, it is to be understood that all matter hereinbefore set forth is to be interpreted as illustrative and not in a limiting sense.

The bevel pinion 46 (Fig. 1) shown in mesh with the gear 47 on the opposite end of the shaft 38 from the pinion 37, is an idler pinion loose on said shaft. It balances the thrusts of the gear 36 and promotes smoother operation.

I claim:

1. In a mount for a gun, in combination, a suitably supported rotatable head upon which the gun is mounted; means for rotating said head and thereby training the gun; and means for elevating the gun comprising a driving gear and a driven gear operatively supported in mesh with each other by said head, the axis of rotation of the driving gear being eccentric to the rotary axis of the head; operative connecting means between the driven gear and the gun for elevating it; and means for operating the driving gear.

2. In a mount for a gun, in combination, a suitably supported rotatable head upon which the gun is mounted; means for rotating said head and thereby training the gun; and means for elevating the gun comprising two bevel gears operatively supported in mesh with each other by said head, one of said gears lying in a plane transverse to the rotary axis of the head and the other gear paralleling said axis, the rotary axis of said transverse gear being eccentric to the rotary axis of the head; means for operating said transverse gear; and operative connecting means between the other gear and the gun for elevating said gun.

3. In a mount for a gun, in combination, a suitably supported rotatable head upon which the gun is mounted; means for rotat-

ing said head and thereby training the gun; and means for elevating the gun comprising gears operatively supported in mesh with each other on said head, the axis of one gear being eccentric to said rotary axis of the head; means for rotating the eccentrically mounted gear and through it the second gear; and means between said second gear and the gun for elevating the gun.

4. In a mount for a gun, in combination, 75 a rotatable head upon which the gun is mounted; a base upon which said head is rotatably supported; means for rotating said head and thereby training the gun; means for elevating the gun comprising a driving gear and a driven gear operatively supported 80 in mesh on said head, the axis of the driving gear being eccentric to said rotary axis of the head; and rotary hand wheels operatively supported by said base in adjacent concentric 85 relation to each other and respectively operatively connected with the aforesaid rotary head and said driving gear.

5. In a mount for a gun, in combination, a rotatable head upon which the gun is mounted; a base upon which said head is rotatably supported; means for rotating said head and thereby training the gun; and means for elevating the gun comprising a driving gear and a driven gear operatively supported in 95 mesh with each other by said head, the axis of rotation of the driving gear being eccentric to the rotary axis of the head; operative connecting means between the driven gear and the gun for elevating it; and means for 100 operating the driving gear, said driving gear operating means comprising a flexible shaft inside the aforesaid head which is hollow, said driving gear being mounted on the end of said shaft, and a hand control operatively 105 supported by said base and operatively connected with the other end of said shaft.

6. In a mount for a gun, in combination, a suitably supported rotatable head upon which the gun is mounted; means for rotating said head and thereby training the gun; and means for elevating the gun comprising a worm wheel gear on the gun, a worm in mesh therewith on a shaft which is transverse to the rotary axis of the head and is operatively 115 supported by said head; a bevel gear and pinion, the pinion being on said shaft and the bevel gear being in a plane transverse to the rotary axis of the head and being supported by said head in a position eccentric to 120 said rotary axis; and means for operating the eccentrically positioned gear.

7. In a mount for a gun, in combination, a suitably supported rotatable head upon which the gun is mounted; means for rotating said head and thereby training the gun; and means for elevating the gun comprising a worm wheel gear on the gun, a worm in mesh therewith on a shaft which is transverse to the rotary axis of the head and is opera- 125

tively supported by said head; a bevel gear and pinion, the pinion being on said shaft and the bevel gear being in a plane transverse to the rotary axis of the head and being
5 supported by said head in a position eccentric to said rotary axis; and means for operating the eccentrically positioned gear; and another bevel gear pinion loose on said shaft in mesh with the eccentrically positioned gear
10 opposite to the first named pinion, the aforesaid worm being located on the shaft intermediate said pinions.

8. In a mount for a gun, in combination, a suitably supported rotatable head upon
15 which the gun is mounted; means for rotating said head and thereby training the gun; and means for elevating the gun comprising gearing operatively supported by said head and positioned relatively to the rotary axis
20 thereof to be given a motion of translation along with said head but without operating the aforesaid gearing supported by the head.

9. In an aeroplane gun mount, in combination, a support for the gun pivotally secured
25 to the bottom of the fuselage of the aeroplane supporting the gun above said fuselage, said support being pivotable transversely relatively to the fuselage to position the gun either above the bottom or over the side there-
30 of; a stationary member extending transversely across the fuselage for guiding the transverse pivoting of the gun support; and releasable means for locating the gun support stationary in various positions along the
35 stationary member.

In testimony whereof, I have signed my name to this specification this 18th day of February, 1930.

WILLIAM L. MACKINE.
